UNITED STATES PATENT OFFICE.

GARNET W. COEN, OF SAN FRANCISCO, CALIFORNIA.

COMBUSTION BAFFLE-PLATE.

1,257,952.

Specification of Letters Patent. Patented Feb. 26, 1918.

Application filed December 26, 1916. Serial No. 138,806.

To all whom it may concern:

Be it known that I, GARNET W. COEN, a citizen of the United States, residing at the city and county of San Francisco and State 5 of California, have invented new and useful Improvements in Combustion Baffle-Plates, of which the following is a specification.

This invention relates to combustion baffle 10 plates for oil or gas fired boiler furnaces.

Many steamships are being constructed wherein it is required that the boiler furnaces be so arranged that either oil or coal fuel may be used and that a minimum 15 amount of time, labor and expense shall be expended in altering the furnaces, when changing from one fuel to the other.

In the installing of fuel oil burning systems in steamships equipped with boilers of 20 the Scotch marine type, it has usually been the custom to build up a brick arch baffle ring in the mouth of the furnaces for the purpose of directing the incoming combustion air into the atomized oil spray, thereby 25 causing the two elements to mix thoroughly at the front end of the furnace so as to create an early combustion of the fuel when ignited. In the case of a steamship where it is desirable to use oil fuel part of the time 30 and coal fuel at other times, the above furnace arrangement is impractical, inasmuch as it would be necessary to tear out the brick rings in order to prepare the furnaces for coal firing, and when changing back to oil 35 fuel these brick rings would have to be built in again. This would necessitate always maintaining a supply of fire brick on hand, as new brick would have to be employed whenever a change was made. This would 40 also entail considerable time, labor and expense.

One of the objects of the present invention is to provide a sectional baffle ring of 45 metal which will perform the duties of the above mentioned brick ring, and which is so constructed that it can be easily and quickly installed or removed from the furnace with the minimum expenditure of time, labor and expense. Another object of the invention is 50 to provide a baffle ring of the character described that will be self-supporting when assembled in the furnace. Another object is to provide means whereby the sections of this baffle ring may be spread apart so as to 55 accommodate furnaces of different diameters.

The invention consists of the parts and the construction and combination of parts as hereinafter more fully described and claimed, having reference to the accompanying drawings, in which—

Figure 1 is a front view of a furnace plate such as is employed on a boiler of the Scotch marine type.

Fig. 2 is a central, longitudinal section 65 through the forward end of the boiler and plate.

Fig. 3 is a front view of the throat plate.

Fig. 4 is a section on line 4—4 of Fig. 3.

Fig. 5 is a front view of the segmental- 70 shaped, over-lapping combustion baffle plates.

Fig. 6 is a section on line 6—6 of Fig. 5.

Fig. 7 is a front view of the throat plate, showing the segmental plates in position. 75

Referring to the drawings in detail, A and B indicate, respectively, the upper and lower halves of a furnace plate such as is employed on a boiler of the Scotch marine type, and 2 the forward end of the cylindrical, corrugated furnace box. The lower half B of the 80 furnace plate is hingedly secured to the upper half, as at 3, to permit it to serve as an ash door when the boiler is burning coal, while the upper half A is bolted to the front 85 of the boiler, as indicated at 4. The lower half is in this instance provided with a door 5 hingedly secured, as at 6, which may be opened to any desired position and secured in said position by means of a chain 7 and 90 a hook 8 to permit the admission of air when the furnace is employing an oil burner, such as indicated at 9.

This burner 9 extends through and is secured in a door 10 which is pivotally mounted, as at 11, in projecting lugs 12 formed on the upper half of the furnace front, and this door carries a second door 13 on its inner side which is pivotally mounted, as at 14, in lugs 15. This door may open in- 100 wardly to permit the admission of air to the upper half of the furnace box; the opening of said door being regulated by means of a chain 16 in a manner similar to the lower door 5.

Adapted to be secured in the furnace box proper, interiorly of the main furnace front, consisting of the plates A and B, is a combustion baffle plate generally indicated at C. This plate consists of a throat plate 110 17 in which is formed a central opening 18. Formed on the inner face of said plate is

an annular, inwardly extending, outwardly flaring flange 19 which surrounds the central opening 18, and formed on the opposite face of the plate 17 is a plurality of 5 radially disposed lugs 20 in which are formed oblong slots 21.

Adapted to be secured to the throat plate, by means of the lugs 20, is a plurality of 10 segmental combustion baffle plates 22. Each of these plates is provided with an inwardly extending lug 23 which alines with the lugs 20, and a bolt extending through said lugs permits each plate to be secured to the throat plate; the oblong slots 21 provided 15 permitting radial adjustment either in an inward or an outward direction to allow the outer periphery of the segmental plates to fit the interior of the furnace box. A corrugated, cylindrical form of fire box is 20 in this instance ideal for the reception of a combustion baffle plate constructed as here shown, as each corrugation forms an annular seat into which the outer periphery of the segmental plates may extend. Each alternate segmental plate 22 is permitted to 25 overlap the adjacent plate, shown at 24, and each of said plates is in turn provided with outwardly extending cooling ribs 25, the function of which will hereinafter be described.

In actual practice, referring to Fig. 2, it will be seen that the combustion baffle plate C as a whole divides the fire-box into a forward air chamber D and a combustion 35 chamber E. The space between the furnace front proper and the plate C depends entirely upon local conditions and may, therefore, be increased or decreased as conditions may require. The central opening 40 18 permits the atomized oil from the burner 9 to freely discharge into the combustion chamber in the direction indicated, and as air is admitted through the lower door 5 and the upper door 13 an ideal distribution 45 and mixing of air with the incoming atomized oil is permitted; that is, equal amounts of air may be admitted both above and below the flame. The outwardly extending cooling ribs 25 being exposed to the comparatively cool incoming air retain the plate C sufficiently cool to prevent overheating and burning, and as all the air admitted to the combustion chamber must pass by the inwardly extending flange 19, it is obvious that this is also kept sufficiently cool 55 to prevent burning of the metal at this point.

Another important advantage obtained where a combustion baffle plate such as here 60 shown is employed is that it permits the air to be directed and brought in contact with the incoming atomized oil practically at the tip of the burner, in this manner permitting the fire to burn from one end of 65 the furnace to the other.

In the case of a steamship where it is desired to use oil fuel part of the time and coal fuel at other times, a combustion baffle plate of the type here shown is of great importance as it can be quickly removed 70 or replaced whenever desired without necessitating a complete cooling down of the boiler. It also eliminates the tearing down or rebuilding of brick rings, and as the plate is at all times maintained comparatively cool by the incoming air, it is obvious that its life and usefulness are unlimited. The insertion of grate bars, when coal is employed, can readily be accomplished as the hinge 3 permits the whole 75 lower section to be opened. This is also important as it exposes the whole ash pit when cleaning the furnace.

The materials and finish of the several parts of the device are such as the experience and judgment of the manufacturer may dictate.

I wish it understood that various changes in the form, proportions and minor details of construction may be resorted to within 90 the scope of the appended claims and that I do not wish to limit myself to the specific design and construction here shown.

Having thus described my invention, what I claim and desire to secure by Letters Patent is—

1. In a boiler of the character described, a two-part furnace front, the upper portion of which is fixed and the lower portion hinged and having a supplemental door 100 hinged thereto, lugs upon the fixed portion, a door hinged to open about the lugs, and a burner carried by said door.

2. In a boiler of the character described, a furnace front consisting of a fixed upper 105 portion, a hinged lower portion, a door hinged to the upper fixed portion to open outwardly, a burner tube fixed to and movable with said door, a second door hinged to the first door to open inwardly, and means 110 to limit the opening of said door.

3. The combination with a furnace of the character described, of a baffle plate having a central throat piece and means to secure said plate within the furnace, said means 115 comprising segmental plates carried by said throat piece, and means to radially adjust said plates about said throat piece to bring them into engagement with the wall of the furnace.

4. In a boiler furnace of the character described, a furnace front with upper and lower independently adjustable draft doors, a burner fixed in conjunction with the upper door, a throat with a central opening 125 and exterior lugs, and radially disposed segmental baffle plates radially adjustable upon said lugs.

5. A boiler furnace fire box having a corrugated periphery forming a succession of 130

annular seats, in combination with segmental baffle plates, the outer peripheries of which engage and are secured in an annular seat.

5 6. A cylindrical corrugated fire box having circular baffle plates formed of segments with projecting lugs and an open central throat with lugs having radial slots upon which the baffle segments are adjustable.

10 7. A boiler furnace including a cylindrical corrugated shell, a baffle plate formed of circular segments, concentric cooling ribs projecting therefrom, and a throat with lugs upon which the segments are adjustably mounted to engage with the corrugated shell at different points and vary the size of the draft chamber between the baffle plate and the furnace front.

15 8. The combination with a furnace having an air inlet chamber and a combustion chamber, of means to vary the relative proportions of said air inlet chamber and said combustion chamber, said means comprising a baffle plate having a central throat, peripheral supports for said plate within the furnace and at various distances from the front thereof, and means to adjust the periphery of said plate to bring said periphery into engagement with any one of said supports.

20 25 30 9. A boiler furnace having a front with a

fixed upper segment and a lower segment hinged thereto, an outwardly opening draft door on the lower segment, a door pivotally mounted upon the fixed upper segment, and a burner fixed thereto, a draft door upon this door above the burner, an open throat through which the burner discharges, surrounding segmental baffle plates, and means to adjust said plates and vary the space between them and the furnace front. 40

10. The combination with a cylindrical fire box, of a circular baffle plate comprising an open central throat, and concentrically disposed segmental plates radially adjustable about said throat to vary the perimeter 45 of said baffle plate.

11. The combination with a cylindrical fire box, of a circular baffle plate comprising an open central throat, and concentrically disposed segmental plates radially adjustable about said throat to bring the outer peripheries of said segmental plates into engagement with the interior of the fire box. 50

In testimony whereof I have hereunto set my hand in the presence of two subscribing 55 witnesses.
